UNITED STATES PATENT OFFICE.

SAMUEL E. FOREMAN, OF PADUCAH, KENTUCKY.

AUTOMATIC CARBURETOR CONTROL.

1,419,963.

Specification of Letters Patent. Patented June 20, 1922.

Application filed June 1, 1921. Serial No. 474,238.

To all whom it may concern:

Be it known that I, SAMUEL E. FOREMAN, a citizen of the United States, residing at Paducah, in the county of McCracken and 5 State of Kentucky, have invented a new and useful Automatic Carburetor Control, of which the following is a specification.

This invention relates to carburetors, and more particularly to a thermostatically controlled regulating means employed in connection with the gas valve of a carburetor for adjusting the supply of fuel to the carburetor according to the heat of the engine.

15 A further object of the invention is to provide a device of this character which may be readily and easily applied to motors now in use, it being unnecessary to alter the construction of the motor to accomplish 20 the positioning of the device.

With the foregoing and other objects in view which will appear as the description proceeds, the invention resides in the combination and arrangement of parts and in 25 the details of construction, hereinafter described and claimed, it being understood that changes in the precise embodiment of the invention herein disclosed, may be made within the scope of what is claimed, without departing from the spirit of the invention.

Referring to the drawing:

Figure 1 is an elevation of a device constructed in accordance with the present invention, an engine manifold and carburetor being indicated in dotted lines.

Figure 2 is a sectional view taken on line 2-2 of Figure 1.

Referring to the drawing in detail, the 40 reference character 5 designates a sleeve or collar to be secured to the exhaust manifold of an internal combustion engine, the manifold in the present drawing being shown in dotted lines, and being indicated by the reference character 6.

A bar 7 has its upper extremity pivotally connected with the sleeve or collar 5 as through the screw 8, the bar 7 being however formed of suitable spring material to 50 cause a pressure to be exerted at the lower extremity thereof, resulting in the gear 9 carried thereby, being forced into engagement with the pinion 10.

The pinion 10 is secured to the valve stem 55 11 to move therewith so that movement of

the bar 7 laterally, will result in a relative movement of the valve stem 11 to accomplish the adjusting of the valve carrier at the lower end thereof.

Associated with the bar 7 is a bar 12 60 which has one end thereof pivotally connected with the bar 7 at a point in spaced relation with the upper end thereof, the connection being made through the pin 13. The opposite end of the bar 12 is secured 65 to the manifold 6, as at 14, to the end that when the manifold 6 becomes heated, the bar 12 will also become heated causing the same to expand, which expansion causes the bar 12 to move.

It follows that since one end of the bar 12 is secured to the manifold, movement of the bar 12 moves the bar 7, the gear 9 moving the stem 11 through the pinion 10 to reduce the quantity of gas passing through the carburetor which in the present drawing is indicated at 15. When the engine cools, it will be seen that the bar 12 moves to its normal position, moving the pinion 10 to admit a greater quantity of fuel to the carburetor. 80

Having thus described the invention, what is claimed as new is:—

1. In combination with the exhaust manifold and carburetor of an internal combustion engine, a pivoted bar supported by the 85 exhaust manifold, a bar having connection with the pivoted bar and adapted to move with the expansion of the manifold, and means for connecting the first mentioned bar and valve of the carburetor, whereby 90 movement of the pivoted bar results in a relative movement of the valve member.

2. In combination with the exhaust manifold, gas regulating valve of a carburetor of an internal combustion engine, a pinion 95 carried by the valve, a pivoted bar having connection with the exhaust manifold and carrying a gear in mesh with the pinion, and a bar having connection with the pivoted bar and adapted to move with the expansion and contraction of the manifold to accomplish the adjusting of the valve.

In testimony that I claim the foregoing as my own, I have hereto affixed my signature in the presence of two witnesses.

SAMUEL E. FOREMAN.
